LINE STRETCHER

Earl L. Howe, Dayton, Ohio

Application July 24, 1946, Serial No. 685,805

8 Claims. (Cl. 254—161)

1

This invention relates to means for stretching lines and for retaining them in a taut condition.

An object of the invention is to provide a simplified and improved form of line-stretching device which is adapted to be connected directly with the line for stretching the same, and after stretching the line, of retaining the same in a taut condition.

Another object of the invention is to provide an improved and simplified form of line-stretching device having an improved and simplified arrangement of a ratchet mechanism for retaining the device in selected positions after placing a line connected thereto in a taut condition.

Still another object of the invention is to provide a line-stretching device that is adapted for use in stretching metal lines, such as fence-lines, and is also adapted for use in stretching an electric fence-line to maintain the same in a taut condition.

Further objects and advantages will become apparent from the drawings and the following description.

In the drawings:

Figure 1 is a perspective elevational view of the line-stretching device of this invention.

Figure 2 is an end elevational view of the line-stretching device illustrated in Figure 1 and is taken in the direction of the arrow 2 thereof.

Figure 3 is a vertical cross-sectional view taken along line 3—3 of Figure 2.

Figure 4 is an elevational view illustrating the application of the line-stretching device to the use of stretching an individual line.

Figure 5 is an elevational view illustrating the application of the line-stretching device for use in stretching an electric fence-line.

The line-stretching device of this invention consists of a body member 10 that is substantially U-shaped and has a base portion 11 and a pair of parallel arm portions 12 and 13. The arm portions 12 and 13 are provided with axially aligned holes 14 and 15 respectively that receive a rod or tubular member 16. The arms 12 and 13 are also provided with small holes 17 and 18 respectively that are adapted to receive a wire for attaching the body member 10 to a desired support. Also, a hole 19 is provided in the base portion 11 through which a line which is to be stretched, passes.

The rod or tubular member 16 extends beyond each of the arms 12 and 13 of the body member 10, and has holes 20 and 21 passing through the extending ends of the rod or tubular member 16. These holes 20 and 21 are placed at right angles

2

to one another and are adapted to receive a suitable tool for rotating the rod 16 within the body 10.

The rod or tubular member 16 is also provided with a radially-drilled hole 22 that is adapted to receive the free end of a line to be tightened.

A ratchet mechanism is provided for holding the rod or tubular member 16 in selected positions. The ratchet mechanism consists of a pair 10 of U-shaped wire members 23 and 24 that pass through radially-disposed holes 25 and 26 in the member 16 adjacent the arm portions 12 and 13 of the body member 10. The holes 25 and 26 are arranged at right angles to one another to thus 15 dispose the U-shaped ratchet members 23 and 24 at right angles to one another. The ratchet members 23 and 24 are thus arranged so that for each 90 degrees of rotation of the tubular member 16, one of the ratchet members may be positioned 20 with the arm thereof disposed over the arms 12 or 13 of the body member 10, as for example, in the manner in which the ratchet member 23 is positioned over the arm 12 as illustrated in Figure 2.

25 A line 30 to be stretched has the free end thereof passed through the hole 19 and extended through the hole 22 in the member 16. A suitable tool, such as the screwdriver 35, is inserted through one of the holes 20 and 21 in the member 16 to rotate the member and thus wrap the line around the member 16, as illustrated in Figures 1 to 3. The initial complete turn of the line 30 around the member 16 will prevent the line from releasing from the member 16. As the line 30 is drawn taut, either of the ratchet members 23 or 24 may be placed over the respective arms 12 and 13 of the body 10 to retain the line in a taut condition.

In Figure 4 there is illustrated an application 30 of the use of the line-stretcher of this invention wherein a wire line 40 is stretched taut between a support such as a building 41 and a post 42. The line 40 extends from the hook 43 of the building 41 and passes through a hole 44 drilled through the post 42. The end of the line 40 is 35 then passed through the member 16 in the manner heretofore described and is drawn taut by rotation of the member 16. Either of the ratchet members 23 or 24 may engage the respective co-operating arms of the member 10 to hold the line 40 in a taut condition.

In Figure 5 there is illustrated an application 40 of the line-stretcher for use in stretching an electric fence-line. In this application of the device 45 vice the electric fence-line 50 extends between

the fenceposts 51 and 52, a suitable insulator 53 being provided at each end of the line 50. A wire loop 54 may have the free ends thereof passed through the holes 17 and 18 in the arms 12 and 13 and suitably fastened.

The line-stretching device of this invention is placed in the electric fence-line 50 with one end of the fence-line 50 being secured to the loop 54 and the opposite free end of the line 50 being passed through the rotating member 16 of the line-stretching device in the manner heretofore described. Rotation of the member 16 will stretch and maintain the line 50 taut, and the line-stretching device will not in any way interfere with the passage of electric current along the fence-line 50.

If desired, of course, the line-stretching device could be positioned between one of the insulators 53 and either fencepost, in which instance the line-stretching device would be out of the electric circuit.

While the device heretofore disclosed and described constitutes a preferred form of the invention, yet it will be understood that the device is capable of alteration without departing from the spirit of the invention, and that all modifications that fall within the scope of the appended claims are intended to be included herein.

Having thus fully described my invention, what I claim as new and desire to secure by Letters Patent is:

1. A device for stretching lines that comprises, a body member having spaced substantially parallel sides, a rod-like member extending between said sides and journaled therein, detent members extending radially through said rod-like member angularly disposed relative to one another and having their ends bent to engage at least one of said sides to prevent rotation of said rod-like member, said rod-like member having means to receive the end of a line for fastening thereto, and further having means for engagement by a tool for rotating said rod-like member.

2. A line-stretching device comprising a body member having spaced substantially parallel sides, a rod-like member extending between said sides and journaled therein, said rod-like member having means for attachment of a line thereto and further having means for engagement by a tool for rotating said rod-like member in said body member, and detent means for preventing rotation of said rod-like member consisting of a plurality of U-shaped members extending radially through said rod-like member disposed angularly relative to one another and freely rotatable in said rod-like member to provide for extension of said U-shaped members over at least one of said sides.

3. A line-stretching device comprising a body member having spaced substantially parallel sides, a rod-like member extending between said sides and journaled therein, said rod-like member having means for attachment of a line thereto and further having means for engagement by a tool for rotating said rod-like member in said body member, detent means for preventing rotation of said rod-like member consisting of a plurality of U-shaped members extending radially through said rod-like member disposed angularly relative to one another and freely rotatable in said rod-like member to provide for extension of said U-shaped members over at least one of said sides, and an opening through said body member substantially radially of said rod-like member

through which a line passes for engagement with said rod-like member.

4. A line-stretching device comprising a body member having spaced substantially parallel sides, a rod-like member extending between said sides and journaled therein, said rod-like member having means for attachment to a line thereto and further having means for engagement by a tool for rotating said rod-like member in said body, and detent means for preventing rotation of said rod-like member consisting of a U-shaped member extending radially through said rod-like member adjacent each of said sides and freely rotatable in said rod-like member for extension over the adjacent side, said U-shaped members being disposed angularly relative to one another to provide for alternate engagement thereof with their respective co-operating sides.

5. A line-stretching device comprising a substantially U-shaped body member, a rod-like member extending through and journaled in the side walls of said U-shaped member, said rod-like member having means for attachment of a line thereto and further having means for engagement by a tool for rotation of said rod-like member in said U-shaped member, and a plurality of substantially U-shaped detent members extending radially through said rod-like member and freely rotatable therein and disposed angularly relative to one another adjacent at least one of the walls of said U-shaped member for alternate extension of said U-shaped ratchet members over the said wall to prevent rotation of said rod-like member.

6. A line-stretching device comprising a substantially U-shaped body member, a rod-like member extending through and journaled in the side walls of said U-shaped member, said rod-like member having means for attachment of a line thereto and further having means for engagement by a tool for rotation of said rod-like member in said U-shaped member, and a U-shaped detent member extending radially through said rod-like member adjacent each of the side walls of said U-shaped member and freely rotatable therein and disposed angularly relative to one another for alternate engagement with the walls of said U-shaped member thereadjacent.

7. A line-stretching device comprising a substantially U-shaped body member, a rod-like member extending through and journaled in the side walls of said U-shaped member, said rod-like member having means for attachment of a line thereto and further having means for engagement by a tool for rotation of said rod-like member in said U-shaped member, a U-shaped detent member extending radially through said rod-like member adjacent each of the side walls of said U-shaped member and freely rotatable therein and disposed angularly relative to one another for alternate engagement with the walls of said U-shaped member thereadjacent, and an opening through the base portion of said U-shaped member through which a line passes for engagement to said rod-like member.

8. A line-stretching device comprising a substantially U-shaped body member, a rod-like member extending through and journaled in the side walls of said U-shaped member, said rod-like member having means for attachment of a line thereto and further having means for engagement by a tool for rotation of said rod-like member in said U-shaped member, a U-shaped detent member extending radially through said rod-like member adjacent each of the side walls

of said U-shaped member and freely rotatable therein and disposed angularly relative to one another for alternate engagement with the walls of said U-shaped member thereadjacent, an opening through the base portion of said U-shaped member through which a line passes for engagement to said rod-like member, and an opening through each of the sides of said U-shaped member closely adjacent the ends thereof to receive means for attaching said U-shaped member to an object.
